CLAMP

William G. Bryant, Brunswick, Ga.

Application May 19, 1944, Serial No. 536,359

2 Claims. (Cl. 294—104)

This invention relates to new and useful improvements in clamps whereby materials of a heavy nature can be firmly grasped preparatory to being shifted or lifted from one position to another.

An important object of the present invention is to provide a clamp which will be self-operating to a firm clamped position as a result of the weight of the material lifted thereby.

Still another important object of the invention is to provide a clamp of the character stated which will be positive acting and substantially fool-proof at all times.

A further object of the invention is to provide a clamp especially adapted for use in shipbuilding whereby portions of a ship can be easily brought and held together while being welded, thus dispensing with the present practice of welding on pad eyes and subsequently burning the same off, after they have served their purpose.

Other objects and advantages of the invention will become apparent to the reader of the following description.

In the drawings:

Figure 1 is a front elevational view of the clamp.

Figure 2 is a side elevational view.

Figure 3 is a horizontal sectional view taken on the line 3—3 of Figure 1.

Figure 4 is a fragmentary vertical sectional view taken substantially on the line 4—4 of Figure 3.

Figure 5 is a fragmentary detailed sectional view taken substantially on the line 5—5 of Figure 3.

Figure 6 is a front elevational view of a slightly modified form of clamp.

Figure 7 is a side elevational view of the clamp shown in Figure 6.

Referring to the drawings wherein like numerals designate like parts, it can be seen in Figure 3, that numeral 5 denotes a substantially flat horizontally disposed block having a substantially rectangular-shaped cut-out 6 for receiving the lower cam-shaped head 7 of an arm 8 which at its upper end has a barrel formation 9 through which a pin 10 is disposed, this pin being secured at its end, by suitable means 11, within the upper head portion 12 of side links 13, 13, these side links extending downwardly and terminating within openings 14 in the slot 5 at opposite sides of the cut-out portion 6.

A fixed shaft 15 is disposed transversely through the block 5 and through the lower por-

tions of the link members 13, 13 and the cam-shaped lower portion 7 of the arm 8.

A line attaching clevis 16 is swingable on the pin 10 (see Figure 1).

5 The block 5 is provided with an oblique extension 17 and a backwardly disposed jaw 18 having a roughened or corrugated jaw face 19 opposed to the cam head portion 7 of the arm 8, as clearly shown in Figures 3 and 4.

10 At the opposite side of the block 5 from the jaw 18 is a reduced eye formation 20 and into this can be tied a lateral line (not shown).

On the block 5 a dog 21 is swingably mounted and is engageable with teeth or ribs 22 on the

15 upper portion of the cam head 7, when the cam head is in clamped position with work which is held against the jaw face 19.

Obviously, when work is positioned between the jaw face 19 and the cam head 7, and a lift

20 is exerted on the clamp, as the arm 8 straightens out, the cam 7 will act against the work and firmly clamp the same against the jaw face 19.

A slightly modified form of the invention is shown in Figures 6 and 7 wherein a block 5a has an arm 8a provided with a similar cam head 7a operating in a like manner against a jaw 18a. This form of clamp can be provided with a dog 21a and may also have a lateral line eye 20a.

The upper end of the arm 8a is likewise provided with a barrel receiving a bolt or pin 10a and a clevis 16a is provided on this bolt or pin 10a.

35 The chief difference between this form of the invention and that depicted in Figures 1 to 5, inclusive, is that eye bolts 25, 25 are provided and disposed vertically through the block 5a, the upper eye ends of which are linked with the lower eye ends of link members 26, 26 which extend upwardly and have apertured heads 27 through 40 which the bolt or pin 10a is disposed as in the manner shown in Figure 6.

45 While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

50 1. A clamp comprising a body, a cam operative on the body, said body being provided with a jaw formation extending to opposed position with respect to the cam, and line attaching means for the cam, said line attaching means 55 consisting of an arm projecting from the cam

and a line attaching clevis at the outer end of the arm, a pin disposed through the clevis and the outer end of the arm and link members between the pin and the body, said link members each consisting of an elongated member having one end secured to the pin and its opposite end pivotally secured to the body.

2. A clamp comprising a body, a cam operative on the body, said body being provided with a jaw formation extending to opposed position with respect to the cam, and line attaching

means for the cam, said line attaching means consisting of an arm projecting from the cam and a line attaching clevis at the outer end of the arm and link members between the pin and the body, said link members each consisting of an elongated member having one end connected to the pin and its opposite end provided with an eye and an eye bolt disposed through the body and having its eye linked with the eye of the corresponding elongated member.

WILLIAM G. BRYANT.
